UNITED STATES PATENT OFFICE.

ORREN J. GREEN, OF AFTON, NEW YORK.

FOLDING COT.

1,350,152.

Specification of Letters Patent. Patented Aug. 17, 1920.

Application filed November 29, 1918. Serial No. 264,676.

To all whom it may concern:

Be it known that I, ORREN J. GREEN, a citizen of the United States, residing at Afton in the county of Chenango and State of New York, have invented new and useful Improvements in Folding Cots, of which the following is a specification.

This invention has reference generally to improvements in that class of invention known as beds and more particularly relates to a folding cot.

The primary aim and object of this invention is to provide a device of the above character which may be readily set up for use or else conveniently folded into a compact form so as to occupy only a minimum amount of space when it is not desired to use the same.

It is an equally important object of this invention to provide a device of the above mentioned character wherein the construction thereof permits of the tightening of the main supporting spring.

More particularly, this invention contemplates the provision of a folding cot of the above character wherein relatively movable frames are employed for supporting the spring to assure of an effective tightening of the spring when so desired.

As a further improvement this invention embraces the provision of coöperative supporting legs and bracing means for assuring of an effective supporting of the movable frames.

A more specific object of this invention includes the provision of improved tightening means mounted on one of the frames for operating against the other frames to cause the frames to be moved away from each other and held in such position consequently causing the tightening of the main spring.

It is an additional object of this invention to provide a device of the above character which is simple in construction, thoroughly reliable and efficient in its purpose and inexpensive in manufacture.

Other objects will be in part obvious and in part hereinafter set forth.

The invention accordingly consists in the features of construction, the combination of elements and the arrangement of parts which will be amplified in the construction hereinafter described and the scope of the application of which will be indicated in the appended claims.

The invention is clearly illustrated in the accompanying drawings, in which:

Figure 1 is a side elevation showing the device in an extended or set up position.

Fig. 2 is a top plan view of the invention.

Fig. 3 is a longitudinal section showing the invention in an extended or open position.

Fig. 4 is a longitudinal section showing the invention in a closed or folded position.

Fig. 5 is a sectional detail of the tightening means.

Fig. 6 is an enlarged transverse sectional view taken on line 6-6 of Fig. 2 in the direction in which the arrows point.

Similar characters of reference are employed in all of the above described views to indicate corresponding parts.

Referring now, more particularly, to the accompanying drawings, there is provided superposed relatively slidably frames 1 and 2, the former being of a rectangular configuration and comprises side bars 3, outer cross bar 4 connected adjacent the ends of the side bars, and an inner cross bar 5 connected at the opposite end of each of the cross bars 3, while the lower frame 2 embodies side bars 6 connected adjacent their outer ends by a cross bar 7. Suitable brackets 8 of a rectangular loop like configuration are connected through the instrumentality of suitable fastening devices 9 to the side bars 6 adjacent the cross bar and also slidably receive the side bars 3 while other similarly constructed brackets 10 are connected to the side bars 3 adjacent the cross bar 4 and slidably receive the outer ends of the cross bar 6 positioned beneath the cross bars 3. Cross rods 11 are arranged transversely between the outer ends of the side bars 3 and 6 adjacent the outer ends thereof as indicated for a purpose that will presently appear. A woven wire spring as indicated by the numeral 12 has its respective ends connected to the upper surfaces of the cross bar 4 of the frame 1 and the cross bar 7 of the frame 2 through the instrumentality of suitable fastening devices 13.

As intimated, improved tightening means have been provided. In reducing this feature of the invention to practice, bearing plates 14 are connected through the instrumentality of suitable fastening devices 15 to the inner surface of the cross bar 110

7. Openings are provided transversely through the cross bar 5 at points opposite the plates 14. Other plates 17 are now employed and are formed with centrally threaded openings 18 which are held in alinement with the openings 16 and connected to the outer face of the bar 5 through the instrumentality of inwardly bent attaching flanges 19 formed on the upper and lower ends of the plates 17 and engageable with the upper and lower edges of the cross bar 5. Screw rods 20 are arranged through the openings 16 and adjustably arranged through the threaded openings 18 in the 10 plate so that the outer ends of the rods bear against the plates 14 and by this arrangement it is apparent that when the wing like handles or finger pieces 21 formed on the inner ends of the rods are twisted the screw rods 20 will be correspondingly adjusted and cause the frames 1 and 2 to move away from each other thus tightening the spring and inasmuch as accidental retrograde movement is prevented by the construction, it is apparent that the spring will be held in such 20 tightened position.

With a view toward providing the supporting means for the frames, opposed pairs of legs 22 are respectively pivotally mounted 30 at their outer ends through the instrumentality of suitable fastening devices 23 to the inner surfaces of the side bars 6 adjacent the cross bar 7 and to the side bars 3 adjacent the cross bar 4. Cross connecting bars 24 have their respective ends connected to the 35 opposed pairs of legs 22 by means of suitable fastening devices 25. Opposed arcuate bracing and supporting members 26 have their lower ends pivotally connected to the 40 inner surfaces of the opposed legs through the medium of suitable pivots 27 and are each reduced on their outer surfaces adjacent the upper end to provide a shoulder 28 designed for bearing against the adjacent cross rods 11 in the frame so as to 45 brace the legs and assure of the proper supporting of the frames. End pieces 29 have their respective ends connected to the inner surface and adjacent the upper ends of the 50 opposed members 26 and when the device is in a set up or extended position as indicated in Fig. 1 these end pieces are arranged above the plane of the spring. In this connection it is to be observed that the lower outer 55 edges of the cross bars 4 and 7 are rounded as at 30 to permit of the curved inner surfaces of the bracing and supporting members being engageable therewith and a con-

sequent arrangement of the end pieces between the cross rods 11 and the adjacent 60 end cross bars of the frame as indicated in Fig. 4 of the drawings. It is apparent therefore that the device may be conveniently folded into a compact form when not in use since the legs lie within plane of 65 the lower edges of the side bars of the lower frame while the bracing members are arranged in close relation with the cross bars as indicated.

It is believed in view of the foregoing description that a further detailed description of the operation of the invention is entirely unnecessary. Likewise it is believed that the advantages of the invention will be readily apparent. 70

As many changes could be made in the above construction and many apparently widely different embodiments of this invention could be made without departing from the scope thereof, and it is intended that all matter contained in the above description or shown in the accompanying drawings shall be interpreted as illustrative and not in a limited sense. It is also to be understood that the language used in 80 the following claims is intended to cover all the generic and specific features of the invention herein described and all statements of the scope of the invention which as a matter of language might be said to 85 fall therebetween.

Having thus fully described this invention what is claimed as new and desired to be secured by Letters Patent is:—

A folding cot including a pair of superposed frames embodying cross bars and slidably connected side bars, a spring connected to the upper faces of the outer cross bars of the frames, cross rods spanning the side bars of both frames adjacent the outer ends thereof, legs arranged in pairs and pivoted to the inner faces of the side bars of the frames adjacent the outer ends thereof, arcuate bracing and supporting members pivotally connected to the legs at an intermediate point and lying against the said side bars, and end pieces spanning the bracing and supporting members at the ends remote from those connected with the legs, the arcuate bracing and supporting members being 100 cut away from the edges engaging the cross bars to provide shoulders for abutting relation with said rods when the legs are in extended position. 105

In testimony whereof I affix my signature. 115
ORREN J. GREEN.
